HOLDER AND SWITCH FOR ELECTRIC
LAMPS

Charles Henri Joseph Anderson and Johannes Hendricus Franciscus van Werd, Eindhoven, Netherlands, assignors to Hartford National Bank and Trust Company, Hartford, Conn., as trustee

Application August 2, 1950, Serial No. 177,264

Claims priority, application Netherlands
August 11, 1949

2 Claims. (Cl. 200—51.09)

1

This invention relates to a holder for securing tubular electric lamps, more particularly low-pressure mercury-vapour discharge tubes, the holder consisting of a housing and a member rotatably supported therein, and to a corresponding lamp cap for a tubular electric lamp.

With a known holder of this type the rotatable member comprises at least two movable contacts which are intended to be connected to an equal number of contacts on the lamp cap and to establish a connection with an equal number of fixed contacts in the housing, in accordance with the position into which the member is moved. This rotation is normally effected by turning the lamp and in a known construction the member is provided with a slot and the lamp cap with a ridge fitting in the slot. The purpose of this construction is to provide a large factor of safety by practically preventing the movable contacts from being alive when there is no lamp in the holder.

The present invention relates to a holder of this type comprising only one movable contact, and has for its object to enhance the safety of such holders and associated lamp caps and to simplify the construction.

It is based on the requirement that the construction of the holder should be such as to permit rotation of the member practically only by means of the lamp cap, i. e. that rotation of this member and making the contact thereon alive by means of instruments or by hand should be prevented so far as is possible. Assuming this purpose to be obtained, it is not necessary to choose the location of this contact so as to be difficult of access, for example in a slot. For the aforesaid reasons the use of a slot in the rotatable member is deemed objectionable, since it would permit of turning the member by means of various simple instruments, for example screw-drivers and coins.

According to the present invention, the rotatable member is provided with a ridge on the side of the introduction of the lamp into the holder. Without using special tools, such as pincers, it is very difficult to turn the member by means of this ridge. The length of this ridge is preferably at least twice its height, in order that the couple to be exerted thereon through a slot in the lamp cap may be duly transmitted. This ridge is preferably formed by that part of the contact provided on the rotatable member which is intended to engage the contact of the lamp cap. Of course, the ridge may alternatively be constituted in part by this contact, whereas the remainder may consist of the material of the member itself.

2

The ends of the ridge may be rounded, thus further impeding its being gripped and facilitating the introduction of the lamp cap. If the lamp holder is constructed in this manner, the associated cap may also be simplified. The known cap is provided with a ridge fitting in the slot of the member and, in its turn, this ridge being furnished with a slot accommodating the contacts. This construction has a limitation in that the length of the cap, measured in the direction of the imaginary axis of the lamp, is comparatively great. Moreover, the ridge has little rigidity, since its slot weakens its side walls considerably. If these side walls should break off, the insertion of the lamp would no longer be possible.

The cap according to the invention has a flat end-surface of insulating material, provided with a slot, on the bottom of which one contact is provided.

20 The term "flat end-surface" is to be understood to mean that the width of the end-surface on either side of the slot is, on an average, at least three quarters of the width of the slot, but preferably exceeds this width.

25 The invention is furthermore based on the recognition of the fact that the shape of the movable contact (on the rotatable member) and of the slot may be chosen to be such that the contact on the lamp cap engaging the slot practically cannot be touched and that the space required for the slot is small, whilst the ridge fitting in the slot is so small that its being gripped is further impeded.

30 The end-surface, remote from the lamp, of the lamp cap according to the invention is provided with a slot, the depth of which, measured from the top of the contact, is at the most 5 mm., the width of the slot being on an average, 4 mm. at the most. Reference is made to the average width of the slot, since it may be desirable to use a little greater width at the area of the contact. In the lampholder, the ridge, according to the invention, preferably has a maximum height of 6 mm. and a maximum width of 3 mm. A similar type of lampholder is described in our copending applications, Serial Nos. 177,261, 177,262, and 177,264 filed August 2, 1950, in which other features of the lampholder are specifically claimed.

40 In order that the invention may be readily carried into effect, an example will now be described in detail with reference to the accompanying drawings in which:

45 Fig. 1 is a view of that side of the holder which is remote from the side of introduction of the lamp and which will be referred to as the back.

The rear wall of the holder and the rotatable member are broken away;

Fig. 2 is a sectional view taken on the line II—II of Fig. 1;

Fig. 3 is a sectional view taken on the line III—III of Figs. 1 and 2;

Fig. 4 is a back view of the movable member and

Figs. 5 and 6 are a sectional view and an end view respectively of a lamp cap for use with the holder shown in Figs. 1 to 4.

Figs. 6a and 6b are plan views from the left hand side of Fig. 5 of, respectively, the assembled lamp cap and only the cap portion.

Fig. 7 is a side view of the same lamp cap;

Fig. 8 is a side view of the holder as seen from a direction, opposite to that, from which Fig. 1 was viewed.

The holder comprises a box 1 of insulating material, for example moulding material. The lower portion of the box has an aperture 2, through which one end of a lamp cap may pass (in Figs. 1, 2, and 8 from above), the lamp being moved parallel to itself. Around this aperture 2, the bottom 3 of the box carries an approximately horseshoe-shaped edge 4, the opening 5 of which is up. This edge 4 (for the greater part shown in dotted lines in Fig. 2) constitutes a location for the movable member 6 which is urged into it by a helical spring 7. The spring 7 rests at the back on a plate 8, which preferably also consists of insulating material and constitutes the rear wall of the holder. At the top it is held under a hook-shaped part 9 of the box 1 and at the bottom by a flanged tube 10.

At the bottom end of the box 1, an elevation 11 constitutes a location 12 for the lower end of the stationary contact 13. This contact is a bent spring, the top 14 of which rests on the periphery of the movable member 6 and the bottom end of which has a hook-shaped part 15 which fits in the location 12. This part has an aperture through which is passed a screw 16 with a nut 17, which are housed between the box 1 and the rear wall 8. The screw can be tightened through an aperture 18 in the box, so that a conductor can be clamped between the nut 17 and the hook-shaped part 15.

The movable member 6 (Figs. 2 and 4) comprises a disc of insulating moulding material, the front side of which is conically bevelled at the edge at 19, so that it is urged into the centre of the location of the edge 4 under the action of spring 7. However, it may also occupy an oblique position, if required by the position of the lamp relative to the holder. A cavity 20 in which the spring 7 fits may be provided at the back of the member 6. The front of this cavity has an elongated aperture 21 through which are passed, from the rear side, two crescent-shaped or semi-circular shaped contact plates 22, which jointly form one contact extending forward from the front surface of the rotatable member in the form of a ridge-like protuberance or ridge. Each of these plates is integral with a strip 23, which extends at the back of the member 6 and forms a contact 24 at the periphery thereof. The member 6 is provided at its periphery with four grooves 25, two of which accommodate the strips 23. The plates 22 are held in the member by the spring 7 with the use of an insulating plate 26.

The lamp cap (see Figs. 5-7) to be used with these lamp holders consists of a cap 27 placed on the tubular lamp, the cap having a circular

aperture 28 with two elongated extensions 29 (Fig. 6b). In Fig. 6 this aperture is indicated by broken lines.

A body 30 of insulating material is passed 5 through these extensions with two lugs 31 and, after providing another insulating plate 32 at the inner side of the cap, it is secured by means of a washer 34 and a flanged tube 33. In this 10 flanged tube, a supply wire 35 to an electrode of the lamp is secured by soldering. The width of the aperture 28 is chosen to be such that sufficient insulation of the flanged tube 33 from the cap 27 is ensured.

The insulating body 30 has furthermore two 15 lugs 36, which are formed by dividing the part, extending beyond the cap, for the greater part by a slot 37 (one side wall of which is shown in elevation in Fig. 5) and by providing a circular groove 38 around the extension adjacent the cap. The bottom of this groove is circular and has two flattened parts (the broken line in Fig. 6). The spacing A between these flattened parts is slightly smaller than the width B of the aperture 5 of the holder (Figs. 6 and 1 respectively).

The operation of this holder will be described 20 with respect to one end of the lamp; on the other side a similar holder is to be imagined.

The holder is mounted whilst the member 6 occupies the position shown in Fig. 2. The contacts 22 cannot now be alive, since the end 14 of the stationary contact 13 does not engage one of the strips 23 (Fig. 4).

One of the ends of the lamp is inserted from 25 above into the holder and turned so that the body 30 passes through the aperture 5, the slot 37 being directed such that the contacts 22 slide into it and engage the conductor 35 by way of the flanged tube 33. If the lamp is turned one quarter turn about the axis of the lamp, the slot 40 37 accommodates the contact plates 22, causes the member 6 to turn, and one of the strips 23 engages the end 14 of the stationary contact 13. This contact may now be alive. At the same time, removal of the lamp is made impossible, since the 45 insulating body 30 forming part of the lamp is locked. A shift of the lamp parallel to its axis is made impossible, not only by the contacts 22 which now occupy a transverse position but also by that part of the body about which the groove 50 38 is provided and which can no longer pass through the aperture 5. A shift of the lamp in the direction of the axis is impossible, since the lugs 36 engage about the edge of the aperture 2 in the bottom of the box 1.

The safety of this holder is ensured, since it 55 is not possible to remove the lamp from the holder without first switching off the contacts 22.

It is possible to insert only one end of the 60 lamp into the holder and subsequently to turn the lamp. The contact on the cap at the other end of the lamp can then be alive through the internal resistance of the lamp, but the slot 37 is narrow and deep so that it is impossible for this contact to be touched.

It is evident from the foregoing that the end 65 of the lamp cap, owing to the absence of a ridge thereon, is mechanically sufficiently strong to resist shocks during its introduction.

Although the lampholder and lamp cap described are particularly intended for use with low-pressure mercury-vapour discharge tubes, so-called fluorescent lamps, they may also be used with tubular incandescent lamps having one 70 contact at each end.

What we claim is:

1. In combination, a lampholder for use with an elongated tubular lamp having a given longitudinal axis and a terminal cap at each end of the lamp having a contact terminal thereon, said lamp holder comprising a housing of insulating material, a fixed contact within the housing, a member rotatable within the housing, a flat, semi-circular-shaped contact on said rotatable member on the side thereof facing the terminal cap and adapted to engage the terminal contact upon insertion of the terminal cap into the lampholder, said flat, semi-circular-shaped contact being adapted to rotate said rotatable member, and means operative upon rotation of said rotatable member with the terminal cap in engagement with the contact thereon to effect an electrical connection between the terminal contact and the fixed contact.

2. In combination, a lampholder for use with an elongated tubular lamp having a given longitudinal axis and a terminal cap at each end of the lamp having a contact terminal thereon, said

lamp holder comprising a housing of insulating material, a fixed contact within the housing, a member rotatable within the housing, a flat, semi-circular-shaped contact on said rotatable member on the side thereof facing the terminal cap and adapted to engage the terminal contact upon insertion of the terminal cap into the lampholder, said flat, semi-circular-shaped contact having a height dimension less than 6 mms. and a width dimension less than 3 mms. and being adapted to rotate said rotatable member, and means operative upon rotation of said rotatable member with the terminal cap in engagement with the contact thereon to effect an electrical connection between the terminal contact and the fixed contact.
